BILLFOLD CONSTRUCTION

Douglas J. Broughton, Springfield, Mass., assignor to Buxton, Incorporated, Springfield, Mass., a corporation of Massachusetts

Application May 27, 1952, Serial No. 290,263

4 Claims. (Cl. 150--38)

1

This invention relates to an improved billfold construction, and more particularly to an improved front wall assembly for billfolds.

One object of the invention is to provide a front wall construction which forms a chassis for the assembly of other structural elements which may take varying forms to meet specific purposes, and may be formed of varying materials.

Another object of the invention is to provide a billfold in which the parts are secured without stitching and in the construction of which substantial savings may be made in the use of an outside covering material of high quality without sacrificing the ability of the parts which make up the front wall construction to withstand long hard usage.

Other objects and advantages in the details of construction will be apparent from the following description and accompanying drawings, in which

Fig. 1 is a front elevational view of a billfold embodying the invention;

Fig. 2 is a plan view of a blank from which the billfold is made;

Fig. 3 is a detail view of an inwardly directed pocket apron secured to an end edge portion of the outer panel member of the front wall assembly as shown by Fig. 2;

Fig. 4 is a detail of a larger outwardly directed apron member overlying the inner side of a front wall outer panel also as shown in Fig. 2;

Fig. 5 is a partial plan view similar to Fig. 2 showing the addition to the assembly of a bridging member and strap connections for the same;

Fig. 6 is a detail of the bridging member;

Fig. 7 is a detail of a stay strap;

Fig. 8 is a detail of a partition member;

Fig. 9 is a partial view of the blank of Fig. 2 showing a first folding operation and the assembly ready for insertion of the partition member of Fig. 8;

Fig. 10 is a similar view showing the partition member inserted with the parts ready for the final folding operation;

Fig. 11 is a fragmentary detail of a modification of the outer edge construction for a front wall end section; and

Fig. 12 is a cross section on line 12-12 of Fig. 1.

In the drawings 1 indicates a rear wall with the customary extension 2 at the top which is folded inwardly against the wall and secured as by cementing to present a finished top edge. The front wall assembly is formed with two spaced end sections generally indicated by the numeral

2

3. Each end section 3 includes an outer panel member extending upwardly from the lower edge of the rear wall, and a panel portion of an inner wall member extending downwardly from the upper edges of the outer panel members. The ends of the billfold are closed by closure flaps 5 extending one from each end edge of the rear wall 1. A bridging member extends across the space between said end sections as indicated at 6, with the ends thereof telescoped between the panel portions of each end section.

The blank from which the body of the billfold is made, as illustrated by Fig. 2, may, if desired, be a two piece structure having an upper and lower portion. The upper portion comprises, as shown, the rear wall 1 and integral therewith the spaced outer front panel members 7. The latter may also have edge extensions 8, cemented as indicated at 9, to the inner ends of two spaced inner wall panel portions 10 of an inner wall member generally designated by the numeral 4. A narrow connector strip 11 connects panel portions 10. The upper portion of the blank of Fig. 2 is formed from leather or other material suitable for the outside surface covering of the assembly and the inner wall member 4 may be of a cheaper material such as a strip of imitation leather or coated fabric. Panel portions 10 overlap the inner side of the material of the upper portion of the blank along the extensions 8 to present finished top edges for the end sections when folded over in the final assembly. The inner wall member 4 may of course be of the same material as, and integral with, panels 7.

The adjacent end edges 12 of the outer panel members 7 may be cut with a concave contour as shown, and between them, extending from the bottom edge of the rear wall member 1, is a tab 13. The material cut from the spaced edges 12 may be preserved and utilized for pocket entrance portions as will be described.

The outer members 7, as indicated at the right hand side of the blank of Fig. 2, are provided with two parallel, spaced cuts 14 and 15. The end edges of the panels may also be centrally notched as at 16. Against the inner face of the members 7 is cemented one end of an inwardly extending apron 17, the cementing being confined to the surface between the edge of a notch 16 and the adjacent cut 14. The apron thus overlies cut 14, as viewed in Fig. 2, and extends inwardly toward the adjacent edge 12, its convex free end edge portion 18 being threaded through the adjacent cut 15. As shown by Fig. 3 the free end portion 18 is cemented to the body portion of the

apron 17. The body of the apron may be inexpensive paper lining stock and portions 18 may conveniently be formed from the leather material cut from between the edges 12 of the spaced end sections, as previously mentioned. The convex curvature of end portions 18 as shown may be derived from the cut making the concave edges at 12.

Also against the inner face of the outer member 7 is placed an apron 19, of inexpensive paper stock, approximately coextensive with the area of member 7, the apron being cemented to the member 7 along a narrow zone adjacent edge 12, as at 20.

At opposite outer end edges of the inner panel member 4, notches 21 may be cut for registration with notches 16 of the outer members 7 when folded over on the same. Adjacent each end edge and spaced inwardly from notches 21 are slots 22 cut in the panel portions 10 to receive the ends of stay straps slidably holding the bridging member 6 between the end sections as will be described. Bridging member 6 is shown by Fig. 6, one of the stay straps 23 by Fig. 7, and the initial assembly thereof with the body of the blank by Fig. 5.

Member 6 may be formed of leather material or the like and top and bottom edge extensions 24 may be folded back and secured to the rear face of the same to present finished edges extending between the end sections in the finished article. Transverse slots 25 are provided adjacent each end of member 6 to receive straps 23. Straps 23 (Fig. 7) are formed at one end with ears 26 for interlocking in the slots 25 as shown by Fig. 5. Member 6, with the straps in place, is then tucked under tab 13 of rear wall 1 with the outer ends of the straps extending beyond the notched edges at 16, all as indicated by Fig. 5.

As the next assembly step (Fig. 9) the inner wall member 4 is folded inwardly over bridging member 6 and the ends of straps 23 are passed through slots 22 of inner panel portions 10. Connector strip 11 of member 4 overlies tab 13 adjacent the lower edge of member 1. A partition member 27 (Fig. 8) with transversely cut end slots 28 is then superposed on the panels 10 with its edge tucked under the tab 13 (Fig. 10), the free ends of straps 23 being threaded through slots 28 of the partition member 27.

This completes the assembly of the elements forming the front wall and the assembly is then folded onto the rear wall as shown in Fig. 1. Prior to or after the assembly has been folded onto the rear wall, the projecting ends of straps 23 are folded around the adjacent edges of members 10 and 7 and are cemented or otherwise secured to the outer face of the latter, as indicated in dotted lines at the left of Fig. 10.

The ends of the billfold are now closed by folding the end closure flaps 5 onto the outer faces of the adjacent outer panel members 7 and inserting the ends of the flaps through the adjacent cuts 14, the portions of the flaps inwardly of the cuts being cemented to the inner face of the said panel members. Preferably and as shown the flaps 5 are provided with ears 29 which interlock with the ends of cuts 14.

When desired, the outer end edges of the inner panel members 10 may be secured to the corresponding edges of the outer panels 7. A preferred manner of accomplishing such securement is shown in Fig. 11 where the members 10 are provided with extensions 30 at each side of notch 21, these extensions being folded over and se-

cured to the outer face of panels 7 in the same manner and at the same time that the ends of strap 23 are secured, as previously described. As will be apparent the secured ends of straps 23 and extensions 30, if the latter are present, are concealed by flaps 5.

After the front wall assembly has been folded onto the rear wall and prior to or after the end closure flaps 5 have been secured in place, the free end of tab 13 extending above the connector strip 11 is cemented to the inner face of the rear wall, as shown in Fig. 12. The connector strip 11 is thus anchored to the rear wall at the bottom of the bill compartment, and the inner panel members 10, which extend to the bottom of the bill compartment are held against separation at their lower adjacent corners. With these corners so held the front wall assembly and the several elements which make it up may be modified to meet a range of billfold needs and structural modifications.

As shown, the structure permits an advantageous multiple pocket arrangement making multiple use of the panels in combination with relatively inexpensive curtain or lining materials. As will be apparent, the provision of the apron 17, having its outer end secured to the inner face of the end edge portion of outer panel 7 and its inner end, finished with the leather portion 18, extending outwardly through slot 15, forms, when the inner end of closure flap 5 is secured to the inner face of panel 7, a pocket 31 between the apron 17 and panel 7. At the same time a pocket 32 is formed between the apron 17 and oppositely directed apron 19. A third pocket 33, has one wall formed by the apron 19 and the other wall formed by the outer end portions of the bridging member 6 and the adjacent inner panel 10.

What is claimed is:

1. In a billfold having a rear wall and a front wall, the latter wall including spaced outer panel members extending upwardly from the lower edge of the rear wall, inner panel members extending respectively from the upper edges of the outer panel members downwardly between the adjacent outer panel member and the rear wall, means connecting the adjacent ends of the rear wall and outer panel members, each of said inner panel members being substantially commensurate with the adjacent outer panel member, the lower adjacent corners of said inner panel members being connected by a narrow strip extending across the space between the outer panel members, a tab extending from the lower edge of the rear wall intermediate the outer panel members and folded upwardly over and above said narrow strip, the portion of said tab above the strip being secured to the inner face of the rear wall, a bridging member extending across the space between the outer panel members with its ends respectively extending between the adjacent outer and inner panel members, and means to retain the ends of the bridging member in said position.
2. In a billfold having a rear wall and a front wall, the latter wall including spaced outer panel members extending upwardly from the lower edge of the rear wall, end closure flaps extending one from each end of the rear wall over the outer end portions of the adjacent outer panel member and secured thereto, inner panel members extending respectively from the upper edges of the outer panel members downwardly between the adjacent outer panel member and the rear wall, each of said inner panel members being substantially commensurate with the adjacent

outer panel member, the lower adjacent corners of said inner panel members being connected by a narrow strip extending across the space between the outer panel members, a tab extending from the lower edge of the rear wall intermediate the outer panel members and folded upwardly over and above said narrow strip, the portion of said tab above the strip being secured to the inner face of the rear wall, and a bridging member extending across the space between the outer panel members with its end portions respectively extending between the adjacent outer and inner panel members, a pair of strap members slidably interlocked one to each said end portion of the bridging member, slots formed in each inner panel member through which the adjacent strap member extends, the free ends of said strap members being folded around the outer end of the adjacent outer panel member and secured to the outer face thereof beneath the adjacent end closure flap.

3. In a billfold as in claim 2, the outer ends of each inner panel member being provided with a

pair of extensions one at each side of said straps, said extensions being folded around the outer end of the adjacent outer panel member and secured to the outer face thereof beneath the adjacent end closure flap.

4. In a billfold as in claim 2, the outer panel members being each formed with a transverse slot spaced from the outer end thereof, an inwardly directed apron secured at one end to the outer end portion of the inner face of each of said outer panel members and having its free end extending through said slot, and an outwardly directed apron secured at one end to the inner end portion of the inner face of each of said outer panel members and overlying the adjacent inwardly directed apron.
